Primary Examiner — Cynthia R Underwood(74) *Attorney, Agent, or Firm* — Scott Seeley;
EASTGATE IP(57) **CLAIM**

The ornamental design for a cargo net hook, as shown and described.

DESCRIPTION

FIG. 1 is a top-side view of a cargo net hook, including embossed text;

FIG. 2 is bottom-side view thereof;

FIG. 3 is a front-side view thereof;

FIG. 4 is a back-side view thereof;

FIG. 5 is a right-side view thereof;

FIG. 6 is a left-side view thereof;

FIG. 7 is a front-perspective view thereof; and,

FIG. 8 is a back-perspective view thereof.

The broken lines depict portions of the cargo net hook and environment of use and form no part of the claim.
